UNITED STATES PATENT OFFICE

JAMES H. KINDELBERGER, OF WEST LOS ANGELES, CALIFORNIA, ASSIGNOR TO DOUGLAS AIRCRAFT COMPANY, INC., OF SANTA MONICA, CALIFORNIA, A CORPORATION OF DELAWARE

DESIGN FOR A GULL WING PLANE

Application filed October 17, 1931. Serial No. 41,421. Term of patent 14 years.

To all whom it may concern:

Be it known that I, JAMES H. KINDELBERGER, a citizen of the United States, residing at West Los Angeles, in the county of Los Angeles and State of California, have invented a new, original, and ornamental Design for a Gull Wing Plane, of which the following is a specification, reference being had to the accompanying drawings, forming part thereof.

Fig. 1 is a perspective view of the plane.
Fig. 2 is a front view of the plane.

Fig. 3 is a plan view of the plane.

I claim:

The ornamental design for a gull wing plane, as shown.

JAMES H. KINDELBERGER.
